UNITED STATES PATENT OFFICE.

CASPER SINGERMAN, OF SOMERVILLE, MASSACHUSETTS.

TAG-FASTENER.

1,196,307.

Specification of Letters Patent. Patented Aug. 29, 1916.

Application filed December 11, 1915. Serial No. 66,277.

To all whom it may concern:

Be it known that I, CASPER SINGERMAN, a subject of the King of Great Britain, residing at Somerville, in the county of Middlesex and State of Massachusetts, have invented certain new and useful Improvements in Tag-Fasteners, of which the following is a specification.

This invention relates to improvements in tag fasteners.

The primary object of the invention is the provision of a fastener of this character, wherein a tag when fastened thereby to an article of merchandise or the like, cannot be detached therefrom, unless the cord connecting said tag thereto is severed, thereby enabling malicious tampering therewith readily detectable.

Another object of the invention is the provision of a fastener of this character, wherein a tag or the like can be readily and easily secured to an article, merchandise or the like, with despatch, and avoiding the accidental loss of the said tag therefrom.

A further object of the invention is the provision of a fastener of this character, which is novel in construction to assure the permanent securing of the tag to an article, merchandise or the like.

A still further object of the invention is the provision of a fastener of this character, which is simple in construction, thoroughly reliable and efficient in its purpose, strong, durable, and inexpensive in manufacture.

With these and other objects in view the invention consists in the features of construction, combination and arrangement of parts as will be hereinafter fully described, illustrated in the accompanying drawing, and pointed out in the claims hereunto appended.

In the accompanying drawing:—Figure 1, is a perspective view of a tag, showing the fastener constructed in accordance with the invention applied for securing of the cord to an article. Fig. 2, is an enlarged sectional view through the fastener. Fig. 3, is a perspective view of the male member of the fastener.

Similar reference characters indicate corresponding parts throughout the several views in the drawing.

Referring to the drawing in detail, A, designates a tag, which is of the ordinary well known construction, on which is adapted to be written any suitable indicia for

identification purposes, and B, the double cord, which is passed through the opening in the reinforced end of the tag, and looped at C, for the securing of the card thereto. 60

The fastener comprises male and female members D, and E, respectively, the latter member being designed to receive the male member for locking engagement thereof. The male member is formed from a single 65 strand of wire 5, which is bent to provide an eye 6, through which is loosely passed the double stretches of the cord B, and parallel arms 7, which terminate in resilient hooks 8, the bills of which diverge from 70 each other, for a purpose presently described.

The female member E, is a tubiform body 9, in which at one end is inserted the free ends of the stretches of the cord B, and 75 thereafter this end 10, of the body is clenched to the cord for the permanent fastening of the latter therein, while the opposite end of said body is formed with an in-turned annular flange 11, concentrically of 80 an opening 12, formed by a conical wall 13, integral with and extended from the flange 11, interiorly of the body, for a short distance, and through this opening 12, is inserted the hook terminals 8, for their locking engagement with the conical wall 13, thereby securing the male and female members together for the permanent fastening 85 of the cord and tag to an article, merchandise or the like, to prevent the detachment 90 of the tag.

From the foregoing it is thought that the construction and manner of use of the fastener will be clearly understood, and therefore a more extended explanation has been 95 omitted.

What I claim, as new, is:—

1. A fastener of the character described, comprising male and female members, one of said members adapted for permanent connection with one end of a cord, and the other member being adapted for slidably engagement with said cord, the female member including a hollow body having an internal locking rim, the male member including a 100 resilient U-shaped member having hook terminals for insertion within the body to automatically engage the locking rim for permanently fastening the members together. 104

2. The combination with a cord, of a male member formed from a single strand of re- 110

silient wire bent into substantially U-shape with an eye between its limbs to loosely receive the cord, a female member including a tubiform body having one end receiving the end of the cord which is permanently secured therein, an internal truncated conical shaped flange at the opposite end of the

body to form a locking rim, and hook terminals on the limbs of the male member for insertion through the conical flange to automatically engage the same for locking the male and female members together. 10

In testimony whereof I affix my signature.
CASPER SINGERMAN.
